UNITED STATES PATENT OFFICE.

JESSE L. GUINN AND GEORGE L. BLAIR, OF OKOLONA, MISSISSIPPI.

SEED-PLANTER.

SPECIFICATION forming part of Letters Patent No. 241,858, dated May 24, 1881.

Application filed February 26, 1881. (Model.)

To all whom it may concern:

Be it known that we, JESSE L. GUINN and GEORGE L. BLAIR, citizens of the United States of America, residing at Okolona, in the county 5 of Chickasaw and State of Mississippi, have invented certain new and useful Improvements in Seed-Planters; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to improvements in seed-planters wherein a rotating seed-drum is attached to a common plow-standard, with a covering device in the rear of the said drum; and the objects of the improvements are to provide a seed planter and coverer so combined that they may be attached to and detached from a common plow standard or stock without injuring the strength of, or interfering with the utility of, the plow as a separate implement.

25 Our improvement, therefore, consists in a covering device attached to the axle of a seed-drum, such covering device being substantially operated in downward pressure by means of 30 springs extending therefrom to the standard of a common plow, as will be hereinafter more fully set forth and described.

Our improvement also consists in the novel construction and combination of parts, as will 35 be hereinafter more specifically described and claimed.

In the accompanying drawings, making a part of this specification, Figure 1 is a perspective view of our improvements attached to the 40 standard of a common plow. Fig. 2 is a longitudinal sectional view of the seed-drum, and Fig. 3 is a cross-sectional view of the seed-drum.

Reference being had to the accompanying 45 drawings, the letter A represents the stock of a common plow, wherein, at such a height as may best serve the purposes of the draft, is made a hole to receive a bolt. At this point the metallic straps or bows B are secured and 50 extend rearwardly to receive the axle of the seed-drum. These straps or bows are made of

such shape as will provide the requisite breadth for insertion of the drum-axle at their rearends, which form a bearing for the drum-axle and clamp the standard at the forward ends, substantially as shown in Fig. 1 of the drawings.

The letter C represents the rotating seed-drum, having the heads D, which are of greater diameter than the drum part, and have rough or corrugated treading-surfaces. These heads 60 are shouldered to suit the diameter of the drum, as shown in Fig. 2 at a. Around and on these shoulders a the material of the drum is fastened; but the material so secured to the shoulders does not extend entirely around the same, 65 but a space is left open for the purpose of affording an opening through which the seeds are put in the drum. This space is supplied and closed by a stave or slat, which is inserted through the hole b of one of the heads, and 70 reaches the length of the drum, fits into a corresponding slot or hole in the other head, and is secured by any suitable means. In the center of the drum, and on a line with the point of the plow or marker, are the holes c, through 75 which the seeds find exit. In the center of the drum-heads is an axle, d, extending through the drum and beyond the heads, for the purpose of receiving the straps attaching the drum to the plow-standard, and those also of the coverer.

The letter E represents the covering device, and consists of a heavy bar of wood or metal corresponding in length to the length of the seed-drum, and is formed with a rearwardly-inclined or circular surface on the front, so as to strike the soil with a dragging effect and is plain on the rear surface. It is attached to the axle of the seed-drum by the side bars, e, and is provided with the compound spring f, 90 whereof the spring i is fixed in upper surface of the coverer, midway from the ends, and the spring k is fixed in the plow-standard, and extending therefrom fits over the end of the spring i, where the two are keyed together, substantially as seen in Fig. 1 of the drawings. The object of these springs is to press on the coverer and at the same time preserve it in position while in operation, and also insure an even pressure when passing over uneven surfaces.

To effect the objects of our invention in op-

eration, after the several parts and appliances have been completed, the straps or bows which secure the drum to the standard, and those which connect the coverer to the drum, are adjusted to the axle of the seed-drum and secured by the nut applied to the end of the axle. The ends of the straps intended to clamp on the plow-standard are bolted in place, and the ends of the side bars intended to fit on the ends of the coverer are likewise pinned or otherwise secured in position, the springs then inserted and keyed, as described, and the machine is ready to be operated, and this is effected by the progression of the power. The plow or marker lines the furrow, the drum rotates, and the seeds drop from the holes in the furrow, and the coverer following spreads the soil over and covers them up.

It will be observed that the drum and coverer can be attached by inserting, and detached by removing, the bolt which passes through the front ends of the bars and the standard.

It will be also seen that the different parts of the improvements, by reason of the character of the connecting mechanism, may each, in turn, conform to any uneven surface passed in planting, being flexible in their connections.

We are aware that it is not broadly new to

combine with an ordinary plow a revolving seed-hopper and covering-plows with an adjustable means, and therefore no broad claim is made to such invention; but

What we claim as new, and desire to secure by Letters Patent, is—

1. The combination, with an ordinary plow and the curved side bars, B, with the rotary seed-drum journaled to the outer ends thereof, of the side bars, e, journaled to the axle of the seed-drum, the coverer E, and compound spring f, substantially as described, and for the purpose set forth.

2. The improved seed-planter hereinbefore described, consisting, essentially, of the ordinary plow with the curved side bars, B, rotary seed-drum D, journaled to the bars B, the side bars, e, attached to the axle of the seed-drum, the coverer E, vertical spring-bar i, and horizontal spring-bar k, all organized substantially as described.

In testimony whereof we affix our signatures in presence of two witnesses.

JESSE LEE GUINN.

GEORGE LURAY BLAIR.
